(57) **CLAIM**

The ornamental design for a mountable light for a vehicle, as shown and described.

DESCRIPTION

FIG. 1 is a perspective view thereof;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a left side elevational view thereof.

The broken line showing of wire is included for the purpose of illustrating the wire and forms no part of the claimed design.
